CLAIM

I claim the ornamental design for a X- shaped header for an internal combustion engine, as shown and described.

DESCRIPTION

FIG. 1 is a perspective view of a X-shaped header for an internal combustion engine showing my new design;

FIG. 2 is a side elevational view thereof;

FIG. 3 is a top plan view thereof;

FIG. 4 is an end elevational view thereof;

FIG. 5 is an end elevational view of the opposing end of FIG. 4 thereof;

FIG. 6 is a bottom plan view thereof;

FIG. 7 is an elevational view of the opposing side of FIG. 2 thereof; and,

FIG. 8 is a reduced side elevational view showing the X-shaped header for an internal combustion engine in use. The broken line in FIG. 8 depicts environmental structure for illustrative purposes only and forms no part of the claimed design.
